The ornamental designs for a personal watercraft rear grill, as shown and described.

DESCRIPTION

FIG. 1 is a rear, left perspective view showing a personal watercraft rear grill according to a first embodiment of our design;

FIG. 2 is a top plan view thereof;

FIG. 3 is a rear elevation view thereof;

FIG. 4 is a front elevation view thereof;

FIG. 5 is a left side elevation view thereof;

FIG. 6 is a right side elevation view thereof;

FIG. 7 is a rear, left perspective view thereof on a personal watercraft, with the personal watercraft shown in broken lines.

FIG. 8 is a rear, right perspective view showing a personal watercraft rear grill according to a second embodiment of our design;

FIG. 9 is a top plan view thereof;

FIG. 10 is a rear elevation view thereof;

FIG. 11 is a front elevation view thereof;

FIG. 12 is a right side elevation view thereof;

FIG. 13 is a left side elevation view thereof;

FIG. 14 is a rear, left perspective view thereof on a personal watercraft, with the personal watercraft shown in broken lines.

FIG. 15 is a front left perspective view showing the personal watercraft rear grill of FIG. 1 with select broken-lined elements removed for the clarity of illustration;

FIG. 16 is a top plan view thereof;

FIG. 17 is a rear elevation view thereof;

FIG. 18 is a front elevation view thereof;

FIG. 19 is a left side elevation view thereof;

FIG. 20 is a right side elevation view thereof;

FIG. 21 is a rear, left perspective view thereof on a personal watercraft, with the personal watercraft shown in broken lines;

FIG. 22 is a front left perspective view showing the personal watercraft rear grill of FIG. 8 with select broken-lined elements removed for the clarity of illustration.

FIG. 23 is a top plan view thereof;

FIG. 24 is a rear elevation view thereof;

FIG. 25 is a front elevation view thereof;

FIG. 26 is a right side elevation view thereof;

FIG. 27 is a left side elevation view thereof; and,

FIG. 28 is a rear, left perspective view thereof on a personal watercraft, with the personal watercraft shown in broken lines.

Throughout the Figures, where shown: (i) the broken lines showing additional structure of the personal watercraft rear grill and the personal watercraft on which it is shown are for illustrative purposes only and form no part of the claimed design; and (ii) in FIGS. 4, 6, 11, 13, 18, 20, 25 and 27, the dotted/dashed lines immediately adjacent solid lines represent unclaimed boundaries of the claimed design and as such, the configuration of the unshaded surfaces defined by those dotted/dashed lines form no part of the claimed design. Portions of the personal watercraft rear grill not shown in the Figures and not otherwise described in this Specification do not form part of the claimed design.
